18 Claims. (CL 200—137)

The invention relates to thermostatically controlled heating devices and it has particular relation to a thermostatically controlled heating device for hot water tanks.

5 Thermostatic controlling of heater units for hot water tanks and the like involves many difficulties. If an electrical unit is employed, the thermostat should cause closing and opening of an electrical switch controlling the heating unit
0 circuit, without arcing of the electrical current, as such arcing always interferes with uniform operation of the heater, necessitates measures to compensate for deterioration of contact points, and shortens the life of the switch. Moreover, 5 the controlling of this switch should be effected with minimum or no effect on the thermostat, as any interference of this character tends to vary the operation of the latter.

In the fuel burning heater unit, the thermostat must control operation of a valve, and frequently moving this valve prevents operation of the thermostat in the desired manner. Moreover it is important that the valve open and close quickly to avoid drag in operating conditions, and prevent 5 overheating or overcooling of the water.

In either case, it is very desirable that the thermostat operate with minimum or no interference, even though it controls an electric switch, or a fuel valve. Also it is important that the 0 switch be closed or opened rapidly and with great power to avoid arcing of current, and to insure operation of the switch at the proper times without drag in operating conditions. In the case of the fuel valve, it is equally important 5 that the valve close and open at the proper times, likewise with power and rapidity to avoid drag in the control of the heater.

One object of this invention is to provide a thermostatically controlled switch, which is 0 opened and closed rapidly and powerfully to avoid arcing of electrical current or drag in operating conditions, and to insure uniform, accurate and dependable operation of the thermostatic control.

5 Another object of the invention is to provide a thermostatically controlled switch of the above mentioned type, in which such operation of the switch is effected without noticeably interfering with the normal and desired operation of the thermostat, and without undesirable loading of the latter, or undesirable stressing of any parts that might affect operation of the thermostat.

Another object of the invention is to provide a thermostatically controlled electric switch, in 5 which movement of the thermostatic movable

element is highly compounded in a simple manner, with few parts, and without loading of the thermostat in an appreciable manner.

Another object of the invention is to provide a thermostatically controlled fuel valve which 60 is opened and closed rapidly and powerfully, without drag in its movement, and without appreciable loading of the thermostat.

Another object of the invention is to provide a thermostatically controlled heater for hot water 65 tanks and the like, which is very simple in construction, very durable, positive and non-varying in its action, and in general which will insure heating of the water through any given range of temperatures, in a constantly uniform, accurate, 70 and dependable manner.

Another object of the invention is to provide an improved electrical control including a switch in which the contacts are separated and brought together quickly and powerfully and without 75 noticeable arcing of current.

Other objects of the invention will be apparent from the following description taken in conjunction with the drawing, and from the claims hereinafter set forth.

For a better understanding of the invention reference may be had to the accompanying drawing forming a part of the specification, wherein:

Figure 1 is a vertical cross-sectional view of a hot water heater in which one embodiment of the 85 invention is incorporated;

Fig. 2 is a cross-sectional view, on a larger scale, taken substantially along the line 2—2 of Fig. 1, and illustrating the thermostatically controlled switch;

Fig. 3 is a cross-sectional view taken substantially along the line 3—3 of Fig. 2, and illustrating the switch in closed position;

Fig. 4 is a cross-sectional view taken substantially along the line 4—4 of Fig. 2 and illustrating 95 the switch in circuit breaking position;

Fig. 5 is a fragmentary cross-sectional view illustrating how the arrangement shown by Fig. 2 may be employed for controlling a fuel supply valve instead of an electrical circuit;

Fig. 6 is a fragmentary cross-sectional view illustrating a slightly different type of thermostatic coupling for the switch or valve.

Referring to Fig. 1, a hot water tank is indicated at 10 and in the particular type illustrated, an upper compartment 11 is provided for the water and a lower compartment 12 for a heating unit. For heating the water in the compartment 11 a water coil 13 is provided which extends into the lower compartment 12 and surrounds an electrical heat-

80

90

100

105

110

ing unit 14. When the heating unit is energized the heat is transferred to the water in the coil 13 and circulation of the water in the latter results in a transfer of heat to the water in the upper compartment. The present invention has particular relation to a thermostatically controlled switch for governing an electric circuit including the heating unit so that the water in the upper compartment 11 may be heated in a predetermined manner.

As shown, the upper end of the coil 13 has a tubular support 15 for guidingly supporting a copper tube 16 which extends through the upper end of the tank. An invar rod 17 is disposed within the copper tube 16 and is connected to the lower end of the latter as indicated at 18. Accordingly, it will be evident that the copper tube and invar rod both are located in the water in the upper compartment and since the copper has a much higher coefficient of expansion than that of the invar rod, expansion or contraction of the copper tube will be relatively greater than that of the invar rod for any variation in temperature of the water in the tank. This variation in movement between the copper tube and invar rod when subjected to varying temperatures, is employed to control the electrical switch which in turn controls the heating unit 14.

Now, as particularly shown by Figs. 3 and 4, it will be noted that the copper tube 16 is threaded into an offset tubular portion 21 of a switch housing indicated at 22, and such tubular portion is threaded at its free end so that it may be threaded into the upper end wall of the hot water tank and hence maintained rigidly in position. From this it will be evident that the free end of the copper tube disposed in the hot water in the tank, may move inwardly or outwardly as its temperature increases or decreases respectively, and that the switch housing and the end of the copper tube connected thereto will be maintained rigidly in position as a result of the connection between the housing and the tank. Inasmuch as the copper tube will expand and contract more than the invar rod 17, movement of the latter at that end opposite its connection with the copper tube, is employed for controlling the electric switch. The manner in which this is accomplished will now be described.

The invar rod extends through the housing 22 in slidable relation therewith, and on the opposite side of the housing is threaded into a manually controlled disc 24, which has a tubular portion 25 closely fitting but slidable in an opening in the housing wall so that movement of the end of the rod will be positively and accurately guided through the housing. Inwardly of the disc 24, a block 26 is slidably mounted on the rod and between the block and the end of the disc portion 25, a strong spring 27 may be provided, which is of such strength that in normal operation of the switch, or full control, pull on the invar rod will compress it little, if any. Inwardly of the block 26, a second block 28 seats on the opposite housing wall and the invar rod likewise slidably projects through this block. The spring 27 in one capacity may constitute a safety feature to prevent possible breakage in the event the temperature continued to rise for any reason whatever. This spring especially seems desirable in the larger types of switches and fuel controls.

The upper surface of the block 28 is provided with a V-shaped projection 30 and the lower surface of the block 26 is similarly provided with a V-shaped projection 31, the latter projection be-

ing substantially in alignment with the axis of the invar rod 17 while the projection 30 is disposed slightly to one side and between this axis and the end of the housing wall adjacent the rod. Between the blocks 26 and 28, the rod loosely passes through an arm 32 which has a V-shape notch 33 adapted to receive the projection 31, and a V-shape notch 34 adapted to receive the projection 30. It should be understood that the notches are of sufficient angular dimensions that fulcruming movement of the arm 32 will be permitted although of course the sharp edges of the projections will seat in the apices of the notches.

The arm 32 extends longitudinally in the housing 22 and as shown best by Fig. 2, has its free end bifurcated to provide legs 35 and 36. Each of the legs 35 and 36, as best shown by Fig. 3, has a notch 37 formed in its end face which is of V shape, and such notches on both legs receive V shaped ends 38 of a U shaped arm 39 disposed between the end of arm 32 and that end of the housing remote with respect to the invar rod connection. The angle between the sides of the V shaped ends of the member 39 is smaller than the angle between sides defining the notches 37 so that the member 39 may fulcrum in such notches between limits defined by the difference between such angles, although it is apparent that the edges of the ends 38 will fulcrum in the apices of the notches.

Screws 40 and 41 threaded through opposite sides of the housing 22 and having trunnion portions 42 and 43 on their inner ends, are provided to guide and position the member 39, and such trunnions project respectively into elongated openings 45 formed in the legs of the member 39 adjacent the V shaped ends thereof. The width of these slots closely corresponds to the diameter of the trunnion portions but the slots are longer than such diameter to permit, if necessary, such as when any wear occurs, some movement of the member 39 longitudinally of the arm 32 and with respect to the trunnions.

Adjacent the notches 37, the legs 35 and 36 of the arm 32 are provided with inwardly directed projections 47 and 48 which in this instance constitute inner end portions of screws 49 and 50. The inner ends of the screws, or the projections, are V shaped as shown in Fig. 4, with the apex of the V portions directed away from the notches 37. Such V shaped projections extend into notches 50 formed in the end faces of legs 51 and 52 of a second U shaped arm 53 disposed between the legs 35 and 36 of the arm 32. It, of course, should be understood that the notches 50 have side walls directed at an angle to each other which is greater than the angle of the V shaped projections 47 and 48 so that the member 53 may fulcrum within limits on such projections, and that the apices of the projection seat in the apices of the notches. The base portions of the U-shaped members 39 and 53, respectively, have screw connections 55 and 56, to which opposite ends of a spring 57 are connected. This spring is of extremely strong character and it will be evident in view of the provision of elongated slots 45 for receiving the trunnions 42 and 43, that the spring will maintain the member 39 seated in the notches 37 without interference as a result of the trunnions engaging the end of the openings 45, and that the member 53 likewise will be maintained strongly fulcrumed on the projections 47 and 48. Accordingly, the spring exerts its force through the members 39 and 53

against the bases of the notches 37, and against the projections 47 and 48, and with no effect on moving the arm 32 lengthwise of the housing.

The lower wall of the housing as shown in Fig. 4, is provided with an insulated contact screw 60 which extends through the wall into a position where it may be engaged by the base portion of the U-shaped member 53. A second contact 61 is threaded through the same wall of the housing in a position where it may be engaged by the base of the U-shaped member 39, and these contacts are connected in suitable electrical circuits to the heater unit 14 so that when the contacts are bridged by a conductor, the heater unit 10 will be energized and when the contacts are separated from the conductor, the heater unit will 15 not be energized. The U-members 39 and 53 together and in conjunction with the arm 32 may constitute this conductor and when they engage 20 the contacts 60 and 61 it is apparent that the heater unit will be energized.

It is apparent also that as long as the arm 53 engages contact 60, the current will be completed as current may flow from the screw 61 and 25 through the housing 20, arms 32 and 53, to the contact 60. Thus the circuit remains completed during pivotal movement of arm 39 away from screw 61, until arm 53 leaves screw 60.

Also as shown by Fig. 4 a relatively strong 30 spring 62 is disposed between the lower side of the arm 32 and the housing wall and in such position that it urges the arm 32 upwardly. Screws or suitable adjusting members 63 and 64 also are threaded through the opposite wall of the 35 housing for engagement respectively with the opposite sides of the base portions of U members 53 and 39. These screws as shown are substantially aligned with the contact screws 60 and 61.

In operation of the heater unit and thermostatically controlled switch, attention is first directed to Fig. 3 which shows the U members 39 and 53 engaging the contact screws 61 and 60 respectively, and hence the unit 14 is energized. As the water in the tank becomes warmer, it is 45 apparent that the copper tube 16 will elongate and hence pull the invar rod 17 further into the tank. As this occurs, it is apparent that the block 26 will be moved toward the arm 32 and hence that the V projection 31 will be urged 50 against the apex of notch 33 in the arm. As the projection 30 is seated in the notch 34, this movement of the invar rod and block 26 will cause the arm 32 to fulcrum about the projection 34 and hence the free end of the arm to move toward 55 the lower housing wall, against the action of spring 62. As the free end of the arm 32 moves downwardly, the U member 39 will fulcrum about the trunnions 42 and 43 although slight longitudinal movement of the member may occur as 60 a result of the arcuate movement of the arm. As the member 39 so fulcrums, it is apparent that, the end of the spring connected thereto will be moved upwardly and when this movement is sufficient, to substantially align the spring 57 with 65 the projections 47 and 48, the spring moving past the dead center or neutral position, will cause the arm 53 to leave contact 60 and move into engagement with screw 63. Owing to the strength of the spring 57, and the fact that it is 70 under considerable tension, this movement of arm 53 is instantaneous and actual tests show that there is no drag in its movement away from the contact. Such tests show also that arcing of electrical current as the arm leaves the contact, is 75 eliminated. Simultaneously, or substantially so,

with the movement of arm 53, the spring 57, causes the arm 39 to move against the screw 64.

At this time it is desired to call attention to the manner in which the movement of the invar rod is compounded in operating the switch. Ordinarily the range of temperature change will only be such as to cause a movement of the invar rod a very small distance, as for example one thousandth of an inch. This movement is magnified at the free end of arm 32, for example 30 times. In turn, any movement of the free end of arm 32 causes a movement of the base portion of U member 39, which may be magnified, for example, 5 times. It follows that any movement of the invar rod is compounded, for example, 150 times in a movement of the base portion of arm 39.

When the circuit is so broken, the water may then begin to cool, and as it cools the invar rod moves outwardly, and the spring 62 consequently moves the arm 32 upwardly, from the position shown in Fig. 3. As this movement continues, spring 57 will finally be brought into action to throw the arms 39 and 53 reversely, and the electric circuit will again be completed.

It has been stated that arm 39 is moved quickly to screw 64 by spring 57, when the arm 32 in moving downwardly reaches the centerline position, and conversely, the arm 39 is moved quickly to screw 61 by spring 57, when the arm 32 in moving upwardly reaches the center line position. Seemingly, when the arm 32 has so moved downwardly, and arm 39 moves toward screw 64, the spring 57 acting through arm 39 tends to fulcrum the latter about the trunnions 42 and 43, and hence to move arm 32 against the action of spring 62. It appears that this force of spring 57, co-acting with the tensioned condition of the invar rod spring 27 and compressed condition of the copper tube, which parts naturally act to relieve their tensioned and compressed condition, is sufficient to overcome spring 62 sufficiently to permit such movement of arm 32 still further and arm 39 to screw 64. While this appears to be a reason why arm 32 moves to allow arm 39 to move to screw 64, possibly other conditions may be more or less responsible, as for example, the infinitesimal character of movement of the arm 32 at the invar rod end, or possibly a slight resiliency or give in the parts, or a slight permissibility of play. Conversely, when the invar rod moves up, as the temperature decreases, and the arm 32 moves past the centerline sufficiently to permit arm 39 to engage screw 61, the movement of arm 32 may be permitted and caused as a result of spring 57, in combination with spring 62, overcoming spring 27. At any rate, arm 39 quickly and rapidly moves to its extreme positions when the thermostat has moved or allowed arm 32 to move to the centerline position.

Adjustment of the disc 24 permits a variation in the high and low temperature of any given range. To vary the range, the positions of screws 61 and 64 or one of them may be varied, and it is evident that if the inner ends of the screws are spaced farther, the base of arm 39 moves through a greater distance. The nearer the inner end of either screw is to the casing wall, the more arm 32 will have to move to cause arm 39 in leaving such screw to bring the spring to its neutral line position and hence to operate the switch. While the neutral position is mentioned, actual use of the device shows that it is impossible to dead center the spring as it will always move past such so called neutral line. The more screws 60 and 64 are

spaced, the greater the range of temperature and vice versa. Also, the range of temperature might be varied by adjusting screws 60 and 63 or one of them. Preferably however it is desired to adjust 5 screws 60 and 63, or at least screw 60, according to voltage of the electric current used, or in other words if a higher voltage is employed, such screws will be spaced a greater distance, and particularly screw 60 will be threaded further out of the casting. In the event a different voltage is utilized, and it is desired to maintain the same temperature range, the variation in spacing of screws 60 and 63, may be compensated for, by a reverse variation in spacing of screws 61 and 64, or one of 10 them as the case requires.

As shown by Fig. 5, the arrangement previously described may be employed to control a fuel valve such as a valve for controlling the flow of gas to a gas burner. In this construction, instead of 20 using a screw contact 60, a valve 70 may be connected to the base of the U-member 53 and a valve seat 71 provided in the wall of the housing. Of course in this type of construction the housing will be sealed against the escape of fuel except 25 through the valve and an opening will be provided for the flow of the fuel either into the housing or out of it to supply fuel either to the burner or to the housing depending upon whether or not the valve is connected directly to the burner or merely 30 supplies fuel to the housing and the latter in turn supplies fuel to the burner. It will be appreciated, of course, that the valve will close and open powerfully and quickly to entirely eliminate "drag", and operate substantially in the same way 35 as the arm 53.

The construction shown by Fig. 6, is similar to those previously described except that the spring 27 is eliminated. It may be stated here that while the spring 27 is preferably used, especially for 40 large types of controls and as a safety feature, and that the spring may be of assistance in permitting arm 39 to move to its extreme positions, engaging the screws 61 and 64, a quick and powerful movement of such arm is obtained even in its 45 absence. Actual use of devices of this character without spring 27, shows that the arm 32 so moves, and in a very rapid manner.

Although but one specific embodiment of this invention has been herein shown and described, 50 it will be understood that numerous details of the construction shown may be altered or omitted without departing from the spirit of this invention as defined by the following claims.

I claim:

55 1. A thermostatic control for heat exchange units comprising a support, a member fulcrumed on the support, means including a thermostat for moving the member about its fulcrum, a pair of arms fulcrumed respectively at spaced points on 60 the free end of the member, a tensioned spring connecting the free ends of the arms, and means for fulcruming one of such arms on the support.

2. A thermostatic control for heat exchange units comprising a support, a member fulcrumed 65 on the support, means including a thermostat for moving the member about its fulcrum, a pair of arms fulcrumed respectively at spaced points on the free end of the member, a tensioned spring connecting the free ends of the arms, and means 70 for fulcruming one of such arms on the support, said last mentioned means being such as to allow the spring to seat such one arm on its fulcrum on the member.

3. A thermostatic control for heat exchange 75 units comprising a support, a member fulcrumed

on the support, means including a thermostat for moving the member about its fulcrum, a pair of arms fulcrumed respectively at spaced points on the free end of the member, a tensioned spring connecting the free ends of the arms, and means for fulcruming one of such arms on the support, said last mentioned means being such as to allow the arm to move longitudinally of the member.

4. A thermostatic control for heat exchange comprising a support, a member fulcrumed on the support, means including a thermostat engaging the member close to its fulcrum for moving the member, an arm extending beyond the free end of the member and fulcrumed on the latter, means pivotally mounting the arm on the support adjacent its fulcrum on the end of the member, whereby a small movement of the thermostat means highly compounds the movement of that end of the arm remote with respect to its fulcrum, a second arm fulcrumed on the member between the fulcrums mentioned and extending toward the first fulcrum, a tensioned spring connecting the remotely disposed ends of the arms, and means on the support for adjustably limiting the throw of one of the arms, as the 100 spring passes its fulcrum point.

5. An electrical control comprising a support, a member fulcrumed on the support, means for moving the member about its fulcrum, a pair of arms fulcrumed respectively at adjacent points 105 on the free end of the member, a tensioned spring connecting the free ends of the arms, means for fulcruming one of said arms on the support, and an electrical contact on the support adapted to engage one of said members.

6. An electrical control comprising a support, a member movably mounted on the support, arms movably engaging the member at adjacent points to permit pivotal movement of the arms relative to the member, and projecting in opposite direction from such points, means for fulcruming one arm on the support, a tensioned spring connecting remotely disposed ends of the arms, an electrical contact adapted to be engaged by one arm, and means for moving the member.

7. An electrical control comprising a support, a member movably mounted on the support, arms movably engaging the member at adjacent points to permit pivotal movement of the arms relative to the member, and projecting in opposite directions from such points, means for fulcruming one arm on the support, a tensioned spring connecting remotely disposed ends of the arms, an electrical contact adapted to be engaged by one arm, means for moving the member, and means for limiting 130 pivotal movement of the arms.

8. An electrical control comprising a support, a member movably mounted on the support, an arm fulcrumed on the member, another arm movably engaging and projecting from the member 135 in a direction opposite to the first arm, means for fulcruming the second arm on the support, a tensioned spring connecting free ends of the arms, an electrical contact adapted to be engaged by one arm, and means for moving the member in a direction transversely of the spring.

9. An electrical control comprising a support, a member movably mounted on the support, arms fulcrumed on the member and projecting in opposite directions therefrom, means fulcruming one arm on the support at a point intermediate its ends but permitting movement of the arm in its own plane towards and from the member, a tensioned spring connecting free ends of the arms, means for moving the member in a direction 145

- transversely of the spring, and an electric contact operatively engageable by one of the arms. 10. An electrical control comprising a support, a member movably mounted on the support, arms 5 fulcrumed on the member and projecting in opposite directions therefrom, means fulcruming one arm on the support at a point intermediate its ends but permitting movement of the arm in its own plane towards and from the member, a 10 tensioned spring connecting free ends of the arms, means for moving the member in a direction transversely of the spring, and an electric contact operatively engageable by one of the arms, said fulcrums for fulcruming the arms on the member 15 being of substantially knife edge character. 11. An electrical control comprising a support, a member movably mounted on the support, an arm fulcrumed at one end on the member, a second arm having one end adjacent the fulcrum 20 and projecting in a direction opposite to the first arm, means fulcruming the second arm intermediate its ends on the support, a tensioned spring connecting remotely disposed ends of the arm, means operatively connecting the member and 25 the inner end of the second arm to cause fulcruming movement of the latter during movement of the member, and means including an electrical contact for limiting fulcruming movement of the first arm when the spring passes the dead center 30 position relative to said arm. 12. An electrical control comprising a support, a pair of arms disposed generally in end-to-end relation, a tensioned spring connecting remote ends of the arms, means fulcruming one arm intermediate its ends on the support, movable control 35 means fulcrumingly supporting the end of the other arm and operatively engaging the inner end of the arm fulcrumed on the support, and means including an electrical contact for limiting fulcruming movement of the arm fulcrumingly supported on the movable means, said last- 40 mentioned arm being free of any fulcruming engagement with the support. 13. An electrical control comprising a support, an elongated member fulcrumed on the support, a 45 pair of arms disposed generally in end-to-end relation adjacent the outer end of the member, means fulcrumingly supporting the inner end of one arm on the free end of the member, means operatively connecting the inner end of the other arm with the member, means fulcruming the last- 50 mentioned arm intermediate its ends on the support, a tensioned spring operatively connecting the free ends of the arms, and means including an electrical contact for limiting fulcruming movement of the first arm, said first arm being free 55 of any fulcruming engagement with the support between the electrical contact limiting means and the fulcrum for the arm. 14. An electrical control comprising a pair of 60 arms disposed in generally end-to-end relation, a tensioned spring operatively connecting free ends of the arms, movable means operatively engaging the inner ends of the arms for moving such ends transversely to the spring, means for 65 effecting movement of the free end of one arm during and in a direction opposite to the movement of the movable means without moving the free end of the other arm in said direction until 70 the spring passes its dead center position, and means including an electrical contact for limiting movement of the free end of the latter or other arm. 15. An electrical control comprising a support, a member movably mounted on the support, arms 80 pivotally mounted on the member and projecting in opposite directions therefrom, a tensioned spring connecting free ends of the arms, means operable upon movement of said member for effecting pivotal movement of the free end of one arm and the end of the spring connected thereto in a direction opposite to the movement of the member and prior to any substantial movement in said opposite direction of the other end of the spring connected to the other arm, and electrical contact means for limiting movement of the last mentioned arm after the spring passes its dead center position. 16. An electrical control comprising a support, a member movably mounted on the support, arms 85 pivotally mounted on the member and projecting in opposite directions therefrom, a tensioned spring connecting the remote ends of the arms, a fulcrum on the support for fulcruming one arm intermediate its ends and intermediate the 90 ends of the spring and operable upon movement of said member for effecting movement of the free end of said arm and the end of the spring connected thereto in a direction opposite to the movement of the member and prior to movement in said opposite direction of the other end of the spring connected to the other arm, and electrical contact means for limiting movement of the last mentioned arm after the spring passes its dead center position. 100 17. An electrical control comprising a support, an elongated member fulcrumed at one end of the support, arms pivotally mounted on the free end of the member and projecting in opposite directions therefrom, a tensioned spring connecting the remote ends of the arms, a fulcrum on the support for fulcruming one arm intermediate its ends and intermediate the ends of the spring and operable upon movement of the member for effecting movement of the free end 105 of said arm and the end of the spring connected thereto in a direction opposite to the movement of the member and prior to a similar movement of the end of the spring connected to the other arm, and an electrical contact means for limiting movement of the last mentioned arm. 110 18. An electrical control comprising a support, an elongated member fulcrumed on the support, control means for moving the member, a pair of arms disposed in generally end-to-end relation at the free end of the member, means 115 fulcrumingly supporting adjacent ends of the arms on the free end of the member, a tensioned spring connecting remote ends of the arms, and means on the support fulcrumingly engaging one arm between its ends and between the ends of the spring, so that the free end of this arm and the end of the spring connected thereto will be positively moved in a direction opposite the pivotal movement of the member when the latter is moved, the other arm being free of fulcruming engagement with the support between the end of the spring connected thereto and its end fulcrumed on the member. 120 135 140
